CLAIM

The ornamental design for a combined tee slot cleaner and shovel, as shown.

DESCRIPTION

FIG. 1 is a perspective view of a combined tree slot cleaner and shovel showing my new design;

FIG. 2 is a top plan view thereof;

FIG. 3 is a front elevational view thereof;

FIG. 4 is a rear elevational view thereof;

FIG. 5 is a left side elevational view thereof with the right side being a mirror image thereof;

FIG. 6 is a bottom plan view thereof;

FIG. 7 is a perspective view of a second embodiment of the design;

FIG. 8 is a top plan view thereof;

FIG. 9 is a front elevational view thereof;

FIG. 10 is a rear elevational view thereof;

FIG. 11 is a left side elevational view thereof with the right side being a mirror image thereof; and,

FIG. 12 is a bottom plan view thereof.
